MECHANISM FOR CONTROLLING WEB MATERIAL

Filed June 14, 1947

INVENTOR.

JOHN F. BANNON

BY

BY
Benj. T. Rauber

ATTORNEY

Apparatus for controlling the feed of fabric to a treating apparatus, comprising a U-shaped lower part having an inlet leg and an off-take leg, a pair of displaceable plates, one at the level of the upper limit of fabric in the inlet leg and the other at the lower level, these plates being so positioned that the weight of fabric or cloth at the respective levels will displace the plates in such a way as to operate control switches, and when the weight of fabric is removed from the plates they will resume their normal positions.

UNITED STATES PATENT OFFICE

2,521,440

MECHANISM FOR CONTROLLING WEB MATERIAL

John F. Bannon, Providence, R. I.

Application June 14, 1947, Serial No. 754,781

1 Claim. (Cl. 270—79)

1

My invention relates to a fabric treating apparatus particularly to a mechanism for controlling the feed of fabric to a treating apparatus. More particularly my invention relates to a type of treating apparatus known as a "J-box."

The J-box type of apparatus as heretofore constructed is of a general U-shape having a long leg into which the fabric is fed and a shorter leg from which the fabric is withdrawn. The fabric, which may be contracted to a rope form, or in open width, is fed into the upper end of the inlet leg by a suitable feed roller and is led by suitable mechanism in horizontal layers. As the fabric piles up in the J-box it is pressed by the weight of the super adjacent layers into a lower part of the apparatus, is then withdrawn through the shorter leg on the opposite side by means of a suitable withdrawing element. While in the J-box the fabric may be heated or washed or treated with a bleach, or with other chemicals, the J-box providing sufficient time and conditions for the treatment.

Inasmuch as the rate of feeding in of the fabric may at times vary from the rate at which it is withdrawn, either by variations of the speed of the feed and off-take mechanisms or from other causes, the level of the piled up fabric in the intake leg may fall to a point at which the period of time in the J-box may be too short for the required treatment, or if the off-take is slow relative to the feed the fabric may pile up in the box to such a point as might clog the feeding mechanism.

My present invention provides a mechanism whereby the feeding of the fabric is so controlled as to maintain the fabric in the intake leg between an upper and lower level.

In my present invention I provide a pair of displaceable plates or elements, one at the level of the upper limit of fabric in the inlet leg and the other at the lower level. These plates are so positioned that the weight of fabric or cloth at the respective levels will displace the plates in such a way as to operate control switches, and when the weight of fabric is removed from the plates they will resume their normal positions. Preferably the plates are hinged at their respective upper edges to the side wall of the intake leg and are pressed outwardly by resilient means so as to receive the weight of the piled up fabric and be displaced. A shield spaced a short distance above the upper plate prevents the displacement of this plate by the impact of the downwardly fed fabric but permits its displace-

ment by the static weight of accumulated layers of fabric.

The control of the motor for feeding the fabric may be effected by an electric circuit so arranged that a displacement of the upper plate by a pile of fabric or cloth will operate a switch to stop or reduce the speed of the feeding mechanism until the layer of fabric falls below the level of the lower displaceable plate which will then return to its normal position and cause the feeding mechanism to start or resume its normal speed. This position will be maintained as long as, or until, the level of the fabric is sufficient to displace the upper control plate.

15 The various features of the invention are illustrated by way of example in the accompanying drawing which shows diagrammatically a vertical section of a J-box having the displaceable control plates and an electric circuit for controlling a fabric feeding motor.

20 In the embodiment of the invention shown in the accompanying drawing a J-box 1 is provided with a U-shaped lower part 2, a relatively short off-take leg 3 and a feed or inlet leg 4 which extends upwardly above the upper end of the off-take leg 3.

25 At its upper end the leg 4 may be provided with an inlet 5 through which a length of fabric 6 is supplied. The fabric 6 passes over a feed roller 7, which may be of usual construction, and thence downwardly through an eyelet or slotted member 8 suspended by a swinging arm 9 to swing from one side to the other of the box so as to lay the fabric in horizontal folds or layers, as indicated at 10.

30 35 If the fabric is being fed in rope form it may pass through an eye 11, which may be fed transversely, and thus distribute the fabric in a criss-cross formation. The means for reciprocating the eyes 8 and 11 are of well known construction and are, therefore, not illustrated.

40 45 On the wall of the inlet leg 10 is mounted an upper control plate 12 and a lower control plate 13. These plates normally project slightly into the J-box but are pressed downwardly against the inner surface of the wall of the leg by a weight of fabric in the event that the fabric rises above the level of the plates. The plates may be of any suitable construction provided they permit the free and unobstructed passage of the fabric and are displaced by the weight of the fabric at or above their level.

50 55 When the plate 12 is displaced by the weight of fabric against the wall of the inlet leg it operates a control mechanism to decrease the speed

of, or stop, the feed roller 7. If and when the level of the piled up fabric should fall below the level of the lower plate 13 this plate will move inwardly or away from the wall of the J-box and this movement will actuate the control mechanism to start the motor or to increase its speed. This condition will be maintained until the level of the fabric rises above the level of the plate 12. Any suitable control mechanism may be employed. By way of illustration an electric control is shown diagrammatically in the drawing.

As illustrated an electric circuit is connected in the circuit, or in the control circuit, of an electric motor 14 which drives the feed roll 7 through a belt 15, or other transmission mechanism, and a driving pulley 16.

This control circuit comprises a lead wire 17 leading to a switch 18 which is operated by the plate 12 to open the circuit and stop, or decrease, the speed of the motor 14 when the plate 12 is displaced against the wall of the J-box. This serves to open the switch.

From the switch 18 a lead wire 19 leads to a second switch 20 which is connected to the lower displaceable control plate 13 in such a manner that the switch is opened when the plate 13 is displaced against the wall of the J-box and closed with the plate as soon as it is in normal position. When the level of fabric falls below the level of the plate 13 the latter, therefore, swings into the J-box and closes the switch 20. At the same time the switch 18 will be closed and the circuit will then be closed through a lead wire 21, an electro-magnet 22 and a lead wire 23 leading to the motor circuit 14 and the supply means or source of current 24. The energizing of the electro-magnet 22 serves to close a switch 25 in a shunt circuit 26 which thereby maintains the circuit closed after the switch is opened and until the circuit is broken by the switch 18. The closing of the switch 18 will not restore the circuit until the switch 20 is closed because the electro-magnet 22 cannot be energized until current is established.

The above electric circuit is purely diagrammatic and is given as an illustration only. Its specific arrangement forms no part of the present invention.

To prevent displacement of the plate 12 by the impact of fabric dropping downwardly to the piled up layers below, a shielding plate 27 is mounted above the plate 12 to deflect the down-

wardly passing fabric but to permit fabric to pile up against the plate 12 under plate 27 and displace the former by static pressure. The shielding plate 27 is preferably secured to the wall of the J-box in a downwardly slanting position and at a level to expose the plate 12 to sidewise pressure.

Through the above invention the level of the pile of fabric in the inlet leg is, therefore, maintained between the level of the displaceable control plates 12 and 13.

Having described my invention, what I claim is:

A fabric treating apparatus which comprises a J-box having an intake leg, and an open outtake leg, a feed mechanism, a motor for driving said feed mechanism, an upper displaceable element and a lower displaceable element in said intake leg in position to be displaced by the weight of fabric at the heights of said elements respectively, a control circuit for said motor comprising an upper switch actuated by said upper displaceable element to open said circuit when said element is laterally displaced, a lower displaceable switch to open upon displacement of said lower displaceable element, electro-magnetic means to maintain said circuit closed between the opening of said lower switch and said upper switch, a swinging guide to lay said fabric in transverse layers crosswise substantially throughout the width of said intake leg against said upper displaceable element and a deflector above said upper displaceable element extending inwardly thereover to prevent freely falling fabric from striking said displaceable element directly.
